United States Patent Office.

G. E. HEGERMAN, OF BROOKLYN, NEW YORK.

Letters Patent No. 80,951, dated August 11, 1868.

IMPROVEMENT IN TIN CANS.

The Schedule referred to in these Letters Patent and making part of the same.

TO ALL WHOM IT MAY CONCERN:

Be it known that I, G. E. HEGERMAN, of Brooklyn, in the county of Kings, and State of New York, have invented a new and improved Tin Can; and I do hereby declare that the following is a full, clear, and exact description thereof, which will enable others skilled in the art to make and use the same, reference being had to the accompanying drawings, forming a part of this specification.

Figure 1 represents a sectional elevation of my improved tin can.

Figure 2 is a plan or top view, partly in section, of the same.

Similar letters of reference indicate corresponding parts.

This invention relates to a new tin can, which is to be more particularly used for the keeping and transportation of petroleum and other liquids.

The invention consists, first, in so bending the edges of the plates that form the sides of a rectangular or other prismatic tin can, that the connection between two such adjoining plates may be produced by means of two different strips of solder, thereby insuring greater strength and durability.

The invention also consists in providing a cap for such can, to be closed by means of a screw-plug, that can be removed when the contents are to be discharged.

By means of this plug the can may be opened and closed at pleasure, while the ordinary caps now in use are mostly such that must be destroyed to open the can.

A A, in the drawing, are the sides of a prismatic tin can.

The side edges of each plate A are bent inward at an angle of about thirty degrees, and are then, by a gradual bend, turned out again, as is clearly shown in fig. 2, in which *a* is the aforementioned bent-in portion, *b* the part turned out.

By this arrangement the joint will be doubled, that is, the two plates touch each other at *c*, where *a* commences, and at *d*, where the parts *b* come together.

Two strips, *c* and *d*, of solder can thus be arranged at each joint.

To the cover C of the can is, in one corner, secured, by solder or otherwise, a short nut or cap, B, which is provided with a female-screw thread, and which can be closed by means of a screw-plug, *e*, as shown in fig. 1.

The cover C is perforated below the plug, so that liquid matter may be freely poured into or discharged from the can.

Having thus described my invention, what I claim as new, and desire to secure by Letters Patent, is—

So bending the edges of the plates that form the sides of a sheet-metal can, that there may be two rows, *c d*, of solder applied at the junction of every two adjoining plates, substantially as herein shown and described.

G. E. HEGERMAN.
